US00D985594S

(12) United States Design Patent (10) Patent No.: US D985,594 S
 Narya et al. (45) Date of Patent:  May 9, 2023

(54) DISPLAY SCREEN OR PORTION THEREOF WITH A GRAPHICAL USER INTERFACE

(71) Applicant: Hint, Inc., Pleasanton, CA (US)

(72) Inventors: Shrankhla Narya, San Francisco, CA (US); Diane Marie Gennity, Austin, TX (US)

(73) Assignee: Hint, Inc., Pleasanton, CA (US)

() Term: 15 Years

(21) Appl. No.: 29/811,077

(22) Filed: Oct. 11, 2021

(51) LOC (14) Cl. 14-04

(52) U.S. Cl.

USPC D14/485

(58) Field of Classification Search

(57) CLAIM

The ornamental design for a display screen or portion thereof with a graphical user interface, as shown and described.

DESCRIPTION

The FIGURE is a front view of a display screen or portion thereof with a graphical user interface, showing our new design.

The broken lines illustrate the display screen or portion thereof, and the broken lines form no part of the claimed design.

1 Claim, 1 Drawing Sheet
